DUALLY FREQUENCY MODULATED
ALTIMETERDaniel Blitz, Princeton, N. J., assignor to Radio
Corporation of America, a corporation of Dela-
ware

Application June 24, 1944, Serial No. 541,935

5 Claims. (Cl. 250—1.68)

1 My invention relates to radio altimeters or other distance measuring systems of the frequency-modulated type.

In systems of this type the distance measurement includes an error that is an inherent characteristic of such systems and which is referred to as "fixed error." As pointed out in Sanders Patents 2,222,586 and 2,222,587, "fixed error" results from the fact that the beat frequency signal obtained during each frequency-modulation cycle or sweep may contain a whole number of beat cycles plus a fraction of a cycle. The fraction of a cycle may or may not produce an extra count in the frequency counter, depending upon the phase relation of the beat frequency signal with respect to the modulation sweep. Thus the distance indication may be in error by a certain amount that is called the "fixed error." The above-mentioned patents describe methods of reducing "fixed error." The present invention describes another method of reducing "fixed error" which, in some circuit designs, may have advantages over previously proposed methods and devices.

An object of the invention, as indicated above, is to provide an improved method of and means for minimizing "fixed error" in a radio altimeter or radar system of the frequency-modulated type. A further object of the invention is to provide an improved radio altimeter or radar system of the frequency-modulated type.

In practicing the present invention the system includes a radio transmitter that is cyclically frequency modulated at a comparatively high frequency rate in such a way that there is a periodic slow shift in the mid-frequency or carrier frequency of the frequency-modulated signal. It should be noted that this does not change the band width of the high frequency sweep.

As a result of the comparatively slow carrier frequency shift, the phase of the beat frequency cycles with respect to the beginning and end of each frequency sweep differs for successive frequency sweeps as explained hereinafter. As a result there will be no sustained error in the frequency count; the count will vary from the correct count plus one to the correct count minus one. By making this variation faster than the time constant of the frequency counter or other frequency meter, the "fixed error" is substantially averaged out or eliminated from the distance indication.

The invention will be better understood from the following description taken in connection with the accompanying drawing in which

Figure 1 is a block and circuit diagram of an altimeter embodying the invention;

Figure 2 is a block and circuit diagram illustrating another embodiment of the invention, and

2 Figures 3, 4 and 5 are graphs that are referred to in explaining the invention.

In the several figures of the drawing, similar parts are indicated by similar reference characters.

Fig. 1 shows the invention applied to a frequency-modulated altimeter comprising a transmitter oscillator 10 having a frequency controlling tuned circuit 10a to which is connected a frequency-modulating unit 11. The modulating unit 11 comprises a variable capacitor element 12 and a driving coil 13. The modulating unit may be of the type described and claimed in application Serial No. 471,003, filed January 1, 1943, in the name of Sydney V. Perry and entitled Capacity modulator unit.

The modulating unit 11 is driven by a frequency-modulating current (which may be of sine wave form as shown in Fig. 3) which is supplied through a transformer 14 from a frequency-modulating wave source 16. This current may have a frequency of 120 cycles per second, for example.

In addition to the frequency-modulated current from source 16, there is applied to the modulating unit 13 through a transformer 17 a comparatively low frequency current such as shown in Fig. 4 which is supplied from a source 18 for the purpose of shifting the mean frequency or carrier frequency of the frequency-modulated wave. The sum of the two currents applied to the modulating unit 11 is illustrated in Fig. 5.

The resulting cyclically frequency-modulated wave with a slowly varying mean frequency is radiated from an antenna 21 toward the earth or other wave reflecting surface, and the reflected wave is picked up by a receiving antenna 22 and supplied to a detector or mixer 23. There is also supplied to the detector 23 directly from the oscillator 10 over conductors 24 a frequency-modulated wave that is the same as that radiated from the antenna 21.

As is well known in the art, the two waves combine in the detector 23 to produce a signal having a beat frequency that is a function of the distance to the wave reflecting surface. Because of the low frequency modulation produced by the current source 18, the phase of the beat frequency signal varies at this low frequency, assuming the received wave is being reflected from some fixed distance. The beat frequency signal is amplified by an audio frequency amplifier 26 and supplied to a suitable frequency measuring device such as a frequency counter 27. Preferably, a frequency counter of the general type described in the Sanders patent and Schwartz et al. Patents Nos. 2,228,367 and 2,137,859, respectively, is employed. It should be understood that instead of a frequency counter a suitable fre-

quency selective circuit such as a frequency discriminator and a milliammeter or voltmeter connected thereto may be employed. Whatever the type of frequency indicator, it should have a long enough time constant or sufficient damping or other suitable characteristic to average out signal variations occurring at the rate of the mean frequency variation produced by the current source 18. In the case of a frequency counter, for example, its time constant should be greater than the period of the signal supplied from the source 18.

It will be understood that the slow rate variation in phase of the beat frequency signal, assuming reflection from a fixed distance, results from the fact that the phase of this signal depends upon the relative phase of the directly transmitted wave and the reflected wave at the detector 23, this relative phase changing with the change in frequency of the transmitted wave. The cyclic variation in phase of the beat frequency signal means that at the end of each successive fast frequency modulation sweep the beat frequency signal will end at a different point in the fractional cycle whereby the plus one and minus one errors occur cyclically and can be averaged out by the frequency counter or other frequency indicator.

While the fixed error reducing signal from the source 18 has been illustrated in Fig. 4 as a triangular wave signal, it should be understood that the signal need not be of this particular wave form and may, for example, be a saw-tooth wave signal. Likewise, the frequency-modulating wave from the source 16 may be of any desired wave form such as triangular or sawtooth, for example. By employing the above described method and system, any fixed error in the distance indication is substantially reduced or eliminated.

Fig. 2 shows an altimeter or distance measuring system similar to that shown in Fig. 1 but which differs therefrom in the means for modulating the transmitter oscillator 10. In Fig. 2, the transmitter oscillator 10 is modulated by means of a vacuum tube reactance circuit 31, which is well known in the art, instead of by means of a mechanically variable capacitor unit. The frequency-modulating wave and the fixed error correcting wave from the source 16 and 18, respectively, are added in the input circuit of a vacuum tube amplifier 32 and applied through a transformer 33 to the reactance tube modulator 31. The operation of this system is the same as described for the system of Fig. 1.

I claim as my invention:

1. A distance measuring system comprising a radio transmitter, means for cyclically frequency modulating said transmitter at a certain rate to produce a frequency-modulated wave, means for simultaneously shifting the mid-frequency of the frequency-modulated wave at a periodic rate that is low compared with said cyclic rate, means for transmitting said frequency-modulated wave to a wave reflecting surface, means for receiving the reflected wave, means for mixing the received wave with a portion of the modulated wave transmitted directly from the transmitter to produce a beat frequency signal, a frequency-indicating means, and means for applying said beat frequency signal to said last means whereby a distance indication is obtained, said frequency-indicating means having a time constant or damping period that is longer than the period of said periodic mid-frequency shift.

2. A distance measuring system comprising a radio transmitter, means for cyclically frequency

modulating said transmitter at a certain rate to produce a frequency-modulated wave, means for simultaneously shifting the mid-frequency of the frequency-modulated wave at a periodic rate that is low compared with said cyclic rate, means for transmitting said frequency-modulated wave to a wave reflecting surface, means for receiving the reflected wave, means for mixing the received wave with a portion of the modulated wave transmitted directly from the transmitter to produce a beat frequency signal, a frequency counter, and means for supplying said beat frequency signal to said frequency counter whereby a distance indication is obtained, said frequency counter having a time constant or damping period that is longer than the period of said periodic mid-frequency shift.

3. In a distance measuring device of the character described, a source of oscillatory currents, means for varying the frequency of said currents, means for varying continuously the mean frequency of said currents, means for applying the thus varied currents to an antenna to radiate waves from the point from which distance is to be measured towards a wave reflecting medium, means for receiving at said point the reflected waves and the directly transmitted waves identical with the radiated waves, means for mixing said waves to produce beat frequency waves, and means for demodulating said beat frequency waves.

4. In a distance measuring device of the character described, a source of oscillatory currents, means for varying the frequency of said currents, means for varying continuously at a comparatively low frequency rate the mean frequency of said currents, means for applying the thus varied currents to an antenna to radiate waves from the point from which distance is to be measured towards a wave reflecting medium, means for receiving at said point the reflected waves and the directly transmitted waves identical with the radiated waves, means for mixing said waves to produce beat frequency waves, means for demodulating said beat frequency waves, and a frequency indicating device having a time constant longer than the period of said low frequency variations to which the demodulated waves are applied.

5. A distance measuring system including means for generating waves, means for varying at a certain rate the frequency of said waves about their mean frequency, means for also varying at a comparatively low frequency rate said mean frequency, means for radiating said waves toward a wave reflecting surface the distance of which is to be determined, means for combining the reflected waves with waves transmitted direct from the wave generator which are the same as the radiated waves to produce a beat frequency wave, means for demodulating said beat frequency wave, and an indicating device to which said demodulated wave is applied, said device having the characteristic such that it will average signal variations occurring at said comparatively low frequency rate.
